US0D1057747S

(12) **United States Design Patent** (10) **Patent No.:** **US D1,057,747 S**
(45) **Date of Patent:** **** Jan. 14, 2025**

(54) **DISPLAY SCREEN OR PORTION THEREOF
WITH GRAPHICAL USER INTERFACE**

(71) Applicant: **Brainlab AG**, Munich (DE)

(72) Inventors: **Mohamed Ahmed Fouad Barakat**,
Munich (DE); **Lily Menu**, Munich (DE)

(73) Assignee: **Brainlab AG**, Munich (DE)

(**) Term: **15 Years**

(21) Appl. No.: **29/928,668**

(22) Filed: **Feb. 14, 2024**

Related U.S. Application Data

(62) Division of application No. 29/771,988, filed on Feb.
26, 2021, now Pat. No. Des. 1,021,915.

(30) **Foreign Application Priority Data**

Sep. 22, 2020 (EM) 008175723-0001
Sep. 22, 2020 (EM) 008175723-0002

(51) **LOC (15) Cl.** **14-04**

(52) **U.S. Cl.**

USPC **D14/485**

CLAIM

The ornamental design for a display screen or portion
thereof with graphical user interface as shown and
described.

DESCRIPTION

The sole FIGURE is a front view of a display screen or
portion thereof with graphical user interface showing our
new design.

The outermost broken lines show a display screen or portion
thereof, and form no part of the claimed design. The other
broken lines show portions of the graphical user interface
that form no part of the claimed design.

1 Claim, 1 Drawing Sheet
